UNITED STATES PATENT OFFICE.

PHILIPP MÜLLER, OF LEIPZIG, GERMANY.

DEVICE FOR ATOMIZING AND DRYING OR EVAPORATING MILK AND OTHER LIQUID SUBSTANCES.

1,397,445.

Specification of Letters Patent.

Patented Nov. 15, 1921.

Application filed February 24, 1920. Serial No. 360,907.

To all whom it may concern:

Be it known that I, PHILIPP MÜLLER, a citizen of Germany, residing at Leipzig, Germany, have invented certain new and useful Improvements in a Device for Atomizing and Drying or Evaporating Milk and other Liquid Substances, (for which I have filed applications in Germany, June 18, 1917; Holland, May 27, 1918; Great Britain, June 10 18, 1918; Roumania, July 6, 1918; Italy, June 14, 1918; Denmark, June 21, 1918; Sweden, June 27, 1918; Norway, June 28, 1918; Finland, July 17, 1918; France, Nov. 4, 1918, and Belgium, July 20, 1918,) of 15 which the following is a specification.

My present invention relates to apparatus for drying or evaporating milk and the like liquid substances. It is the object of my invention to provide an improved apparatus 20 by means of which milk or other liquid substances can be dried or evaporated by first atomizing the substance to be treated in any well known manner by means of a pressure medium of a gaseous nature, and thereafter 25 subjecting the atomized substance to the drying action of a gas capable of promoting the action of drying or evaporation. With this object in view my invention consists of a discharging tube extending downward from a container of liquid, and a feeding member for a gaseous pressure medium, which feeding member being of a smaller sectional area than said discharging tube 30 is disposed to extend into the opening of said discharging tube. The feeding member is just below the opening of said disk 35 charging tube provided with a plurality of openings for the emersion of the pressure medium and is preferably surrounded by 40 a second tube which ends a certain distance below said emersion openings and serves as a feeding tube for a gas capable of promoting the drying or evaporation of the atomized substance.

45 In the accompanying drawing I have illustrated an embodiment of my invention, by way of example, in a sectional elevation.

Referring to the drawing, *a* designates a 50 container for the substance to be dried such, for instance, as milk. The milk flows out of the container through the discharge tube *b* within the bottom of said container. Into the opening at the lower end of said discharge tube *b* projects a tube *d* having the 55 upper end closed by means of a cone shaped

top piece *c*, whereby the milk leaving the discharge tube *b* is transformed into an annular jet.

The tube *d* is provided with small orifices *e* closely below the discharge opening of the tube *b*. The tube *d* serves for feeding a pressure medium of a gaseous nature such, for instance, as pressure subjected air. The pressure medium leaving the feeding tube *d* through said small orifices *e* atomizes the 65 annularly shaped jet produced by the closed cone top *c*.

The feeding tube *d* is surrounded by a larger tube *f* through which hot air or any other gas capable of acting as a drying agent 70 for the atomized liquid is supplied. The drying medium may leave the feeding tube *f* through the open end of the same, as indicated in the drawing, or special discharge orifices may be provided therefor. The pressure medium may be fed through a pipe of smaller dimensions than the tube *d* which, in such a case, serves mainly for supporting the coned top *c* the office of which is to transform the outflowing liquid into an annularly shaped or umbrella like jet. The employment of a much smaller feeding pipe 75 for the pressure medium may be advisable when a very high pressure is required for atomizing the liquid to be dried. 85

I am aware that other changes may be made without departing from the spirit of my invention.

What I claim as my invention and desire to secure by Letters Patent of the United 90 States is:—

1. In a device for atomizing and drying or evaporating milk and other liquid substances, the combination of a discharge tube for the substance to be treated with a member 95 projecting into the discharge opening of said discharge tube so as to transform the discharge flow of liquid into an annular jet, said member having discharge openings for a pressure medium within said member, said 100 discharge openings being positioned in proximity to the discharge opening of said tube and another member for feeding a drying medium, the discharge opening of said last named feeding member being disposed below 105 said discharge openings for said pressure medium, whereby the substance to be treated is first atomized and then subjected to the drying action of said drying medium.
2. An apparatus for atomizing and dry- 110

ing or evaporating milk or other liquid substances, comprising, in combination, a container for the liquid to be treated, a discharge tube within the bottom of said container, a feeding tube for a pressure medium, a coned top on said feeding tube, said coned top projecting into the discharge opening of said discharge tube so as to transform the outflow of said discharge tube into an annular jet, said feeding tube having orifices disposed below said coned top and communicating with the interior of said feeding tube for the pressure medium, and a feeding tube for a gaseous drying agent, said last named feeding tube being disposed to inclose said

afore named feeding tube for the pressure medium and terminating a distance below said afore named feeding tube, whereby the substance to be treated is first atomized by means of the pressure medium and thereafter dried by means of the gaseous drying agent. 20

In witness whereof I have signed this specification in the presence of two witnesses.

PHILIPP MÜLLER.
